UNITED STATES PATENT OFFICE

EDWARD S. FATKIN, OF MANSFIELD, OHIO, ASSIGNOR TO WESTINGHOUSE ELECTRIC & MANUFACTURING COMPANY, A CORPORATION OF PENNSYLVANIA

ROTARY-HEARTH FURNACE

Application filed September 19, 1927. Serial No. 220,536.

My invention relates to furnaces and more particularly to furnaces of the tilttable-hearth-tray type.

In furnaces of the above-mentioned type, difficulty has been experienced in providing means for pivotally mounting the hearth tray which will not bind or stick when subjected to heating and cooling of the parts incident to operation of the furnace.

10 It is an object of my invention, therefore, to provide an improved means for mounting a hearth tray which permits the free pivotal movement thereof during the operation of the furnace and which is sufficiently rugged 15 in construction to withstand the relatively high furnace-chamber temperature.

In practicing my invention, I provide, in a rotary-hearth furnace having a plurality of hearth trays therein for containing the material to be heat-treated, means for pivotally mounting said trays upon said hearth comprising a plurality of cupped bearing surfaces adapted to cooperate with convex bearing surfaces formed on said trays and means for preventing relative longitudinal and vertical movement between said bearing surfaces.

In the drawings,

Figure 1 is a view, in vertical section, of a rotary-hearth furnace embodying my invention,

Fig. 2 is a plan view, partially broken away, of a tray-supporting means embodying my invention,

Fig. 3 is a section taken on the line III—III 35 of Fig. 2,

Fig. 4 is a lateral elevation of the hearth tray embodying my invention, and

Fig. 5 is a bottom plan view of a hearth tray shown in Fig. 4.

40 Referring more particularly to the drawings, a furnace embodying my invention comprises annular walls and roof portions built up of suitable refractory heat-insulating material defining an annular furnace chamber, and provided, for structural reasons, with a sheet-metal shell 2 and the usual structural reinforcing irons 4.

A chute 5 for facilitating the discharge of material from said furnace chamber projects 50 through the outer wall of the furnace and is

adapted to communicate with a quench tank, or conveyor, (not shown) in the usual manner.

An annular opening is formed in the bottom of the furnace chamber for the reception 55 of an annular hearth 6, carried upon an annular metallic structure 8, which is mounted for movement through the furnace chamber upon flanged wheels 10 cooperating with a circular rail 12 secured to the furnace foundation.

Sand-seals 14 and 16, of the usual type, are provided between the annular edges of the hearth and the opening in the floor of the furnace chamber.

Rotation of the hearth is effected by an electric motor 18 operatively connected, through suitable gearing 20, to a vertical shaft 22 extending axially of the furnace chamber and hearth. A bevel gear 24, secured to the lower 70 end of the shaft 22, engages a bevel gear 26 suitably secured to a shaft 28 to rotate a gear 30, secured thereto. The gear 30 cooperates with an annular gear rack 32 secured to the hearth structure 8 to effect the rotation 75 thereof.

Upon the hearth 6 are pivotally mounted a plurality of article-carrying hearth trays 40 to be successively tilted to effect the discharge of material therefrom through said discharge 80 chute 5.

The tilting of trays 40 is effected by a lifting rod 42 provided, at the lower end thereof, with suitable means for engaging said trays and provided, at the upper end thereof, with a lateral projection 43 adapted to ride in a continuous cam slot formed in the face of a drum 44, the rotation of which is caused by a motor 46 operatively connected thereto.

90 The structure above described constitutes a tilttable-tray, rotary-hearth furnace of the usual type and, since the specific details of construction thereof form no part of the present invention, a more detailed description 95 thereof is not deemed necessary.

My invention contemplates, more specifically, the provision of an improved pivotal mounting for the hearth trays 40, as herein-after described in detail.

Spaced circumferentially on the upper face of hearth 6 are a plurality of supporting structures indicated broadly as 50. The base of each supporting structure is channeled, 5 as at 51, to receive a projecting portion 52 formed on the refractory hearth to maintain the hearth and support it in fixed relation. The channel is somewhat larger in width than the projecting portion 52 of the hearth to permit relative contraction and expansion therebetween.

Adjacent to the outer edge of the supporting structure, is a pair of bearing faces 54, substantially semi-circular in lateral section, 15 spaced above the base of the supporting structure and having the axes thereof in alignment and substantially perpendicular to a hearth radius passing therebetween.

Peripherally of the support along the inner lateral edge and sides thereof is formed 20 a substantially vertical wall 56 for supporting the hearth tray in operative horizontal position, as hereinafter described.

Extending upwardly from the supporting base, on the lateral sides of the bearing surfaces, are apertured walls 58 which 25 cooperate with the bearing surfaces to form substantially semi-cylindrical recesses.

The hearth trays 40 comprise substantially 30 segment-shaped containers open at the lateral edges thereof adjacent to the outer wall of the furnace.

Depending from the bottom of each tray are two apertured lugs 62 having rounded 35 or convex bearing surfaces formed on the lower ends thereof and adapted to fit into the recesses or concave bearing surfaces 54 formed between the plates 58, with the apertures in the lugs and plates in horizontal alignment.

40 A rod or pin 64 of suitable heat-resistant material is adapted to cooperate with said apertures to maintain the support and the tray in operative relation. The apertures in the lugs and plates are coaxial with the radius of curvature of the bearing surfaces, thereby permitting tilting of the trays. Relative lateral movement between the trays and the supports is prevented by the cooperating 45 plates 58, and the bearing surfaces are maintained in operative relation by the bar 64.

With the structure described, it is obvious 50 that the weight of the tray is substantially all carried by the interfitting concave and convex bearing surfaces formed on the support and tray, respectively, and since the effect of the heat, incident to furnace operation, will affect both surfaces equally, the pivotal movement of the tray will not be affected. On the 55 other hand, if the usual type of pivoted or hinged supporting means with the weight carried by a hinge pin, is employed, the high temperature will result in excessive wear of the hinge elements.

60 65 By my invention, I have provided a pivotal

mounting for a tilttable hearth tray which is efficient and effective in operation at furnace-chamber temperatures. Obviously, although I have described a furnace of a specific type, my invention is not limited in its application, 70 thereto, but is applicable in any connection where a hinge joint may be subjected to excessive heat, as in a furnace chamber.

Various modifications may be made in my invention without departing from the spirit 75 and scope thereof, and I desire, therefore, that only such limitations shall be placed thereon as are imposed by the prior art and set forth in the appended claims.

I claim as my invention:

1. In a bearing for pivotally mounting a 80 hearth tray, for containing materials during the heat treatment thereof in a furnace chamber, comprising a stationary support, a concave bearing surface formed in said support, a support for said tray having a convex bearing surface formed thereon, and means for maintaining said bearing surfaces in cooperative relation.

2. In a bearing for pivotally mounting a 85 hearth tray, for containing materials during the heat treatment thereof in a furnace chamber, comprising a support, spaced concave bearing surfaces formed in said support, a tray, spaced lugs on said tray having convex bearing surfaces formed at the 90 ends thereof, and means for maintaining said bearing surfaces in cooperative relation.

In testimony whereof, I have hereunto subscribed my name this 8 day of Sept., 1927.

EDWARD S. FATKIN.
